UNITED STATES PATENT OFFICE.

EDWARD W. WRIGHT, OF LEXINGTON, OKLAHOMA TERRITORY, ASSIGNOR
OF ONE-HALF TO R. A. CRITCHER, OF LEXINGTON, OKLAHOMA TERRITORY.

SUPPORT FOR CARRIAGE-TOP BOWS.

SPECIFICATION forming part of Letters Patent No. 761,281, dated May 31, 1904.

Application filed February 11, 1904. Serial No. 193,164. (No model.)

To all whom it may concern:

Be it known that I, EDWARD W. WRIGHT, a citizen of the United States, residing at Lexington, in the county of Cleveland, Oklahoma Territory, have invented certain new and useful Improvements in Supports for Carriage-Top Bows; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in flexible supports for carriage-top bows or braces; and the object of the invention is produce a device of this character which is adapted to attach to the metallic frame of the carriage-top and having a goose-neck curve near one end forming a hook or socket for the reception of a bow and so constructed that the hook will yield slightly, so as to take up any jar coming upon the bow, and thereby avoiding unnecessary wear between the contact-points of the hook and bow.

My invention consists, further, in the provision of a device of this character which will be hereinafter fully described and then specifically defined in the appended claim.

I illustrate my invention in the accompanying drawings, which, with the letters of reference marked thereon, form a part of this application, and in which drawings—

Figure 1 is a perspective view showing my bow-supporting device as applied to the frame of a top of the carriage. Fig. 2 is an enlarged detail view of the device detached from the top.

Reference now being had to the details of the drawings by letter, A designates a flexible bar made of any suitable material, which is rigidly held upon the stud B, carried by a metallic framework C of the carriage-top.

Said bar extends nearly the length of a bow D of the top and at A' is bent substantially the shape of a gooseneck, the upper part of

said curved portion being parallel with the shank portion of said bar, and at the location A' said bar is bent at substantially right angles to the length of the shank portion of said bar and is adapted to form a socket to receive the bow D. When the end of the bar is bent in the shape shown in the drawings, it will be observed that the shank portion of said bar will be positioned parallel to the bow and only spaced apart therefrom a distance equal to the diameter of the bar, and owing to the socket portion A' being formed at the location illustrated, a short distance from the curved portion A', sufficient provision is made for allowing the socket-carrying end of the bar to yield slightly to take up the jar coming upon the bow. The entire strain of the bow is adapted to be taken up by the bar, which yields slightly, as does also the socket or hooked end on which the bow rests.

By the provision of a device of this character I have found from practical experience that an efficient means is provided for supporting the bow of a carriage-top and by which supporting means all jar coming upon the bow is taken up and without moving contact between the bow and the supporting arm or bar.

While I have shown a particular shape of device embodying my support for bows, it will be understood that I may alter the shape and dimensions of the same, if desired, without in any way departing from the spirit of the invention.

I am aware that it is common in the art to attach spring-arms to the framework of a buggy-top, in which the bars are either fixed or pivoted to the frame and have hooks at their ends which engage the rear or back bow of a buggy-top, and hence I do not make claim, broadly, for such construction.

Having thus described my invention, what I claim as new, and desire to secure by Letters Patent, is—

A bow-supporting attachment for carriage-tops comprising a flexible bar which is adapted to be fixed at one end to the frame of the top,

said bar being bent longitudinally upon itself and having its extreme upper end bent at right angles forming a hook disposed intermediate the portion of the bar which is bent upon itself and its fixed point, the shank portion of said rod being curved adjacent to its fixed end, as set forth.

In testimony whereof I hereunto affix my signature in presence of two witnesses.

EDWARD W. WRIGHT.
